SLIDE LOOP

Carl E. Anderson, Bloomfield, N. J., and George H. Elwell, New Haven, Conn., assignors to Eastern Tool and Manufacturing Company, Bloomfield, N. J., a corporation

Application November 23, 1940, Serial No. 366,890

4 Claims. (Cl. 24—188)

This invention relates to slide loops adapted for adjustably gripping a strap of wearing apparel and the like, and more specifically to such a type of slide loops provided with an easy and rapid means for threading a strap therein.

The objects of the invention, therefore, are to provide a slide loop comprising in part a pair of loops having the usual upper bar, side bars, intermediate bar structure and lower bars, but into which a strap may be fully threaded behind the upper bar, over the intermediate bar structure and behind the lower bars by means of one direct insertion of a strap therein, as if into one loop alone; to provide in connection with such a slide loop a double stabilizing and effectual strap-gripping and binding element; to provide, with regard to spaced aligned lower bars of a slide loop, a connector permitting certain freedom of movement of the integral arms of a button loop; to provide co-operating means between the strap-binding element and the connector to maintain a locked strap grip against release; and to provide a stop-lift element having the dual function implied thereby.

In the accompanying drawing the Figure 1 is a front elevation of the improved slide loop in readiness to receive a single insertion of a strap; Figure 2 is a side elevation illustrating a single insertion of a strap; Figure 3 is a front elevation of the same slide loop in partial operation; Figure 4 is a side elevation illustrating the strap shown in the previous side elevation, but carried to an advanced threaded condition by a partial operation of the pair of loops; Figure 5 is a front elevation of the slide loop in fully operated erect position; and Figure 6 is a side elevation of the fully threaded slide loop.

Referring more particularly to the accompanying drawing the numeral 1 designates a wire button loop of a particularly type already disclosed in the art and to which this application makes no claim of novelty. The strap-suspension loop 2 of the button loop 1 is of a type in common with most button loops and comprises, in part, the upper bar 3 and the lower spaced aligned bars 4. One of the novel features of this invention lies in the ferrule 5 by which the aligned bars 4 are movably connected, thus giving a continued effect to the bars 4 of the suspension loop 2 for a purpose hereinafter explained. The sheet-metal member 6 is provided with a strap loop 7 having the upper bar 7' and is hinged to the upper bar 3 of the suspension loop 2, as at 8, so that in folded relation, each to the other, the sheet-metal strap loop 7 is placed

in superimposed position with the suspension loop 2 of the button loop 1, as illustrated by the Figure 1. Integrally carried by the sheet-metal member 6, between the hinges 8, are the strap-gripping and strap-binding elements 9 and 10 extending radially from the line of axis of the hinges 8, the element 10 having the greater radial reach than that of the element 9 in order that, as the hinged member 6 is swung from its folded position, the element 10 in passing through the loop 2 may pass into close proximity to the ferrule connector 5 to assume, as herein-after explained, not only a strap-gripping function but also that of binding a strap between it and the ferrule connector 5. While the elements 9 and 10 are illustrated as having teeth, the teeth may be omitted if desired. A stop-lift 11 also is carried by the hinged member 6 integrally to thereby the swung along the rear of the slide loop and engaged, in the absence of a threaded strap, with the ferrule connector 5.

The hinged assembly of the sheet-metal member 6 upon the bar 3 of the button loop 1 incorporates the strap loop 2 of the button loop 1 with the strap loop 7 of the hinged member 6 as a pair of loops 2 and 7 separated by an intermediate bar structure comprising the bar 3 within the groove, an intermediate part of the hinges 8, and thereby carrying radially extending projections in the form of the strap-gripping and binding elements 9 and 10.

In operation, the hinged sheet-metal member 6 being in its folded position down upon the face 1' of the button loop 1 so that the strap receiving loop 7 is in superimposed position with the strap receiving loop 2, as illustrated by the Figures 1 and 2, the end of the strap 12 is inserted directly into and through the superimposed position loops 7 and 2 in the same manner as if the two loops were but one loop, as illustrated by the Figure 2. The hinged member 6 is then manually lifted to swing away from the face 1' of the button loop 1 toward its erect position with the result that, as illustrated by the Figure 3, the thus inserted strap 12 begins to assume its threaded relation to the slide loop and, upon the full erection of the hinged member 6 with regard to the button loop 1, there is provided thereby a pair of loops 2 and 7 in a common plane, as illustrated by the Figures 5 and 6, the strap 12 becoming fully threaded therein by automatically assuming positions behind the upper bar 7' of the strap loop 7, over the front of the intermediate bar structure 2, including the strap-gripping projection 9, under the strap-binding pro-

jection 10 and over and behind the ferrule connector 5. In the final movement of the sheet-metal hinged member 6 to a fully erect position into the plane of the button loop 1, that is, from the position illustrated by the Figure 4 to that of the position illustrated by the Figure 6, the strap-binding element 10 in engagement with the added thickness of the strap 12 is thereby obstructed in its easy passage into and past the loop 2 over the ferrule connector 5 until manually urged by snapping the hinged member 6 into its fully erect position illustrated by the Figure 6, the collapse of the slide loop requiring similar manual urging, but of course in a reversed direction. To insure against accidental collapse of the slide loop, the stop-lift 11, lying next to the strap immediately behind the ferrule connector 5, prevents force, directed against the face 1' of the slide loop while the rear of the slide loop rests against the body of the wearer, resulting in collapse. The stop-lift 11 in its engagement with either the ferrule connector 5 itself or as covered with the threaded strap 12, serves as a stop to prevent farther movement of the sheet-metal hinged member 6 when a fully erect position has been reached. A further function of the stop-lift 11 is in the manner in which it may be manually lifted away from its snug engagement against the rear of the threaded strap 12 to effect an intentional collapse of the slide loop for the purpose of a sliding adjustment of the slide loop along the length of the strap 12.

From the foregoing, the advantages of the improved slide loop become apparent. The manner in which, by means of a sudden thrust of a strap end into the super-positioned folded loops 2 and 7 and the rapid erection of the slide loop parts that the complete threading of the strap therein may be accomplished; the positiveness of the grip and binding of the slide loop upon the strap; and the ease with which adjustment may be had along the length of the strap by means of a quick collapse and restoring to full erection cannot be excelled.

We claim:

1. A slide loop having a face and comprising a pair of relatively hinged loops adapted to be folded into relative superimposed position and unfolded to relatively erect position thereby providing a pair of loops in a common plane and having an upper bar, a hinged intermediate bar and a lower bar, a button connecting means rigidly carried by one of said loops; a strap-binding means rigidly carried by the other of said loops and adapted to thereby be swung from the rear of said face, during the unfolding of said loops, into close proximity to the lower bar structure and into the adjacent loop; whereby a strap in a single insertion may be made to simultaneously enter the combined loops and, upon the unfolding of the loops, to be carried therewith and automatically threaded behind the upper bar, over the face of the intermediate hinged bar and behind the lower bar structure, the binding element in its engagement with the threaded strap being manually urged past the lower bar structure and thereby held against accidental return movement.

2. A slide loop comprising a wire button loop having a face; a strap-receiving suspension loop

having an upper bar and lower aligned bars with which the button loop is provided; a ferrule substantially enclosing and movably connecting the lower aligned bars; a sheet-metal member hinged to said upper bar; a strap-receiving loop rigidly carried by said member and adapted to be superimposed positioned over the face of the strap-receiving suspension loop and to be openly erected therefrom to provide a pair of loops in a common plane; toothed strap-gripping elements of varied radial reach and rigidly carried by, and divergently extending from, the axis line of the hinge portion of said member and adapted to be swung upon the erection of the folded loops from the rear of said face into the suspension loop for projection from said face, the binding element of the greater radial reach passing in close proximity to said ferrule; and a stop-lift also rigidly carried by said hinged member for an arresting engagement with the ferrule at the rear of said face upon the full erection of said loops; whereby a strap upon a single insertion may be made to enter the folded loops and, by their said full erection, to be carried automatically to a fully threaded relation therewith behind the upper bar, over the face of the intermediate hinged bar with its projection and behind the aligned lower bars, the binding element of the greater radial reach in its engagement with the threaded strap being manually urged past the ferrule in strap-binding engagement therewith against accidental return movement, and all farther advance movement arrested by the engagement of the stop-lift with the rear of the strap covered ferrule.

3. A pair of relatively hinged loops adapted for folded superimposed position for the simultaneous reception, as if one loop, of a direct insertion of a strap; a relatively erect open position to which the strap-inserted loops are adapted to unfold, said open pair of loops constituting a slide structure having an upper bar, an intermediate bar and a lower bar in a common plane, the movement of the unfolding loops automatically carrying the inserted strap therewith behind the top bar, over the face of the intermediate bar and behind the lower bar; and means carried by both hinged loops in cooperation with a threaded strap to bind the strap therein and to thereby maintain an erect pair of loops against accidental collapse.

4. A slide loop comprising a wire button loop having a transverse loop with an upper bar and spaced aligned lower bars; a ferrule movably connecting the aligned bars; a sheet-metal member pivotally carried by said upper bar, said member having parallel transverse loop and groove, the latter providing a seat for said upper bar and lugs encompassing the extreme ends of the seated bar; and the sheet-metal loop being adapted for a folded superimposed position relative to the wire loop; strap-binding elements diverging radially from the central portion of the groove upon either side of the seated bar and out of the plane of the sheet-metal member; and a stop-lift arm rigidly carried by the said member and engageable with the rear of said ferrule as the sheet-metal and wire loops lie unfolded in a common plane.
